UNITED STATES PATENT OFFICE

2,559,813

WELT CUTTING DEVICE

Aubrey F. White, North Weymouth, Mass.

Application June 16, 1950, Serial No. 168,451

4 Claims. (Cl. 12—67)

1

This invention relates to machines for cutting strips of weltting such as are used in shoemaking and has for an object to provide such a machine for cutting a strip of generally rectangular cross section, but provided with a stitch groove in its flesh face, in such a manner that the strip may be formed up into a welt having a bead on its upper or grain face between its side edges and which in use may engage close to the upper of a lasted shoe. To this end, the cutting is accomplished, in accordance with this invention, in two stages, the first partly severing an edge portion of the strip inwardly from the flesh face, and the second forming a generally V-shaped cut which produces a core portion and an attached layer within which the core portion may be wrapped, while the partly severed edge portion which is integral with the core portion provides a further layer which may overlie the base strip on the inside of the rib and which may be engaged by the inseam stitching in the manufacture of the shoe and thus hold the welt in its folded condition with the integral bead on its grain face.

For a complete understanding of this invention, reference may be had to the accompanying drawings in which:

Figure 1 is a rear elevation of a welt cutting machine embodying the invention.

Figure 2 is a fragmentary front elevation of the same.

Figure 3 is a left side elevation of the machine.

Figure 4 is a fragmentary top plan view thereof.

Figure 5 is a sectional view on line 5—5 of Figure 4.

Figures 6 and 7 are detail sectional views on lines 6—6 and 7—7, respectively, of Figure 5.

Figure 8 is a perspective view of the rear knife.

Figure 9 is a perspective view of the cut welt strip and

Figure 10 is a cross sectional view of the completed beaded welt.

Referring first to Figures 1, 2, and 3, the machine comprises a suitable support 1 shown as provided with spaced legs 2, this support being provided with a pair of spaced upstanding walls 3 provided with lower and upper pairs of spaced bosses 4 and 5. The bosses 4 are tubular and have journaled therein a shaft 6 provided at one end outwardly of one of the wall members 3, with a lower feed roll 7. Between the bosses 4, the shaft 6 has secured thereto a gear 8. With this gear 8 meshes a long gear 9 carried by a jack shaft 10 suitably supported in spaced ears 11. Also cooperating with the long gear 9 is a gear 12 on a drive shaft 13, this drive shaft 13 being journaled in aligned apertures in the bosses 5. At one end, this drive shaft 13 carries means, such as a belt pulley 14, by which the drive shaft may be rotated as by means of a belt 15 passed

about the drive wheel 14 and leading to any suitable rotating means. Rotation of the drive shaft thus drives the gear 9, the shaft 6, and the lower feed roll 7.

A frame 14 is rockably mounted on the drive shaft 13 and this frame 14 has journaled therein a feed shaft 15 which carries a knurled or otherwise roughened feed roll 16, which, when the frame 14 is in the angular position shown in full lines in Figure 3, is positioned above and in cooperative relation to the lower feed roll 7. The feed shaft 15 carries a gear 17 which meshes with the drive shaft gear 12. The nip between these feed rolls 7 and 16, when the frame is in its lowered position, is adjacent to one edge of a table 20 carried by the support 1. This table has positioned thereon a pair of spaced guide members 21 and 22 which may be secured to the table top by screw and slot means 23 which permits the spacing between these guides to be adjusted in accordance with the width of the welt strip which is to be cut. One of these guides, as 21, is provided with a hold-down 24 which projects across the space between the guides and may overlap the guide 22.

A second hold-down strip 25 may be adjustably fixed to the guide 21 to extend toward alignment with the inner face of the guide 22 to the extent desired. Opposite to the free end of this hold-down strip 25 may be positioned a knife 30, which, as shown best in Figure 5, is provided with a downwardly sloping cutting edge 31 arranged in line with the feed direction of the welt strip, this cutting edge being positioned to cut partly through the welt strip 35 from its top or flesh face adjacent to one edge as shown best in Figure 6. This forms a cut 36 in the flesh face of the welt strip and partly severs therefrom a relatively thin layer 37. This knife 30 is clamped to a holding block 38, which has a vertical groove to receive the knife as shown in Figure 5. This block 38 may be secured as by screw and slot connections 39 with the top face of the table. It will be noted that this knife is in advance of the feed rolls 7 and 16.

Adjacent to the opposite edge portion of the table where the welt strip leaves this table and close to the nip between the feed rolls, there is positioned the cutting edge 40 of a second or slitting knife 41 shown detached in Figure 8. The cutting edge of this knife is of V or angular contour having a substantially straight portion 42 which is substantially parallel to the top face of the table, and the angularly related portion 43 is upwardly inclined and intersects the top or flesh face of the welt strip presented thereto as shown in Figure 7. The cut 36 made by the first knife 30 is therefore positioned spaced from the apex of the V of the knife 41.

It is important that the knife 41 be accurately

positioned vertically so as to provide a layer 45 beneath the horizontal cut 46 of the proper thickness. To this end, the knife 41 is secured to the top face of a block 50 and is adjustable lengthwise thereon by screw and slot connection at 51, backed up by a screw 52 extending through a shoulder 53 along one edge of the block.

The block 50 is slidably guided vertically within a way in the supporting standard 55 which carries the table 29 and its height is adjusted micro-metrically by turning an adjusting screw 56 threaded through the support 1 and bearing against the under face of the block 50. This screw 56 is provided with a knurled head 59 at its lower end by which it may be turned and a circular flange portion 60 thereon suitably graduated may have cooperating therewith an indicating finger 61 which will facilitate positioning of the adjusting screw 56 in any predetermined position. The slide block 50 may be held against the upper end of the adjusting screw as by means of a coil spring 65 seated in a socket 66 therein and secured at opposite ends to a loop 67 in the block and an eye 68 secured to the support 1. A locking screw 70 threaded into the block 50 and passing through a slot 71 in the part 55 and having a clamp collar 72 thereon may be employed to lock the block 50 in any desired adjusted position.

The welt strip to be cut may be inserted beneath the shaft 13 while the frame 14 is tilted upwardly into the dotted line position shown in Figure 3 and pushed forward until it reaches the edge of the knife 41. When the welt is in this position the frame 14 may be brought down into the full line position shown in Figure 3 and there held by a tie rod 75 hinged at 76 to a lug on the frame 14 and having a thumb nut 77 threaded on its lower end which may be brought beneath a slotted lug 78 secured to the support 1 and then tightened to the desired degree to cause the feed rolls to exert the desired pressure on the welt strip. On causing the feed rolls to rotate in the directions shown by the arrows in Figure 3, the welt strip may then be pulled along and the cuts formed as shown in Figures 6, 7 and 9. These cuts define a thin layer portion 46 and a core strip portion 80, one side edge of which is partly cut to form the layer 37. The parts are then wrapped and cemented into the positions shown in Figure 10, the strip portion 80 being partly enclosed within the layer 46 and the layer 37 being turned outwardly to overlie the body portion of the strip to form the completed welt. As before noted, the stitch groove 81 of the welt strip is formed before the strip is presented to the machine of this invention.

When the welt is thus formed up and cemented together, it will be noted that the layer 37 forms a portion integral with the bead on the welt and which is penetrated by the stitching when the welt is incorporated in a shoe so that the cement is not relied upon to maintain the bead in its finished condition.

From the foregoing description of an embodiment of this invention it will be evident to those skilled in the art that various changes and modifications may be made without departing from its spirit or scope.

I claim:

1. A welt cutting machine comprising a table, guides on said table spaced to permit a welt strip to be passed therebetween, upper and lower feed rolls positioned to engage the upper and lower faces of the strip at one edge of said table, a

welt slitting knife positioned adjacent to the nip between said rolls and against the cutting edge of which said strip may be fed by rotation of said rolls, said knife having a cutting edge of V shape with one side substantially parallel to the top face of said table, and the other side extending upwardly, and a knife having a lower cutting edge inclined downwardly lengthwise in the direction of feed and positioned to cut part way through said strip along one edge and at one side of said V cut.

2. A welt cutting machine comprising a table, guides on said table spaced to permit a welt strip to be passed therebetween, upper and lower feed rolls positioned to engage the upper and lower faces of the strip at one edge of said table, a welt slitting knife positioned adjacent to the nip between said rolls and against the cutting edge of which said strip may be fed by rotation of said rolls, said knife having a cutting edge of V shape with one side substantially parallel to the top face of said table, and the other side extending upwardly, and a knife having a lower cutting edge inclined downwardly lengthwise in the direction of feed and positioned to cut part way through said strip along one edge and spaced laterally from the apex of said V.

3. A welt cutting machine comprising a table, guides on said table spaced to permit a welt strip to be passed therebetween, upper and lower feed rolls positioned to engage the upper and lower faces of the strip at one edge of said table, a welt slitting knife positioned adjacent to the nip between said rolls and against the cutting edge of which said strip may be fed by rotation of said rolls, said knife having a cutting edge of V shape with one side substantially parallel to the top face of said table, and the other side extending upwardly, and a knife having a lower cutting edge inclined downwardly lengthwise in the direction of feed and positioned to cut part way through said strip along one edge and at one side of said V cut, said last mentioned knife being positioned to cut in advance of said slitting knife.

4. A welt cutting machine comprising a table, guides on said table spaced to permit a welt strip to be passed therebetween, upper and lower feed rolls positioned to engage the upper and lower faces of the strip at one edge of said table, a welt slitting knife positioned adjacent to the nip between said rolls and against the cutting edge of which said strip may be fed by rotation of said rolls, said knife having a cutting edge of V shape with one side substantially parallel to the top face of said table, and the other side extending upwardly, and a knife having a lower cutting edge inclined downwardly lengthwise in the direction of feed and positioned to cut part way through said strip along one edge and spaced laterally from the apex of said V, said last mentioned knife being positioned to cut in advance of said slitting knife.

AUBREY F. WHITE.
